UNITED STATES PATENT OFFICE.

PERCY L. SMITH, OF LOWELL, MASSACHUSETTS.

BICYCLE-WHIRL.

SPECIFICATION forming part of Letters Patent No. 634,857, dated October 10, 1899.

Application filed September 14, 1898. Renewed June 7, 1899. Serial No. 719,728. (No model.)

To all whom it may concern:

Be it known that I, PERCY L. SMITH, a citizen of the United States, residing at Lowell, in the county of Middlesex and State of Massachusetts, have invented certain new and useful Improvements in Bicycle-Whirls; and I do hereby declare the following to be a full, clear, and exact description of the invention, such as will enable others skilled in the art to 5 which it appertains to make and use the same.

My present invention relates to an improvement in bicycle-whirls, and has for its object the production of a whirl giving certain capabilities of independent movement to the individual bicycles adapted to be propelled by the riders, which is more agreeable to the riders, more perfect in construction, and capable of nicer adjustment and of greater durability than machines of this character here- 10 tofore in use.

My invention consists in the machine hereinafter described, and particularly pointed out in the claims at the end of this specification.

25 In the accompanying drawings, illustrating the preferred form of my invention, Figure 1 is a plan view of a portion of my bicycle-whirl. Fig. 2 is a side elevation showing one of the bicycles in side and one in front elevation, the intervening wheels being omitted for the sake of clearness. Fig. 3 is a plan view of a bicycle-supporting yoke, showing its connection with the guy-rods and a bicycle-frame. Fig. 4 is a front elevation of the 30 same. Fig. 5 is a side elevation of the front-fork yoke shown as attached to the fork and lower chord of the bicycle-frame. Fig. 6 is a plan view of the same, and Fig. 7 is a detail plan view of the front-fork yoke.

40 A indicates a center post, upon which in any suitable manner is rotatably mounted the whirl-ring B, to the outer periphery of which are attached the guy-rods C, extended outwardly in pairs to bicycle-yoke bearings 45 D, rigidly mounted thereon.

E indicates the bicycle-yoke which, as shown, is provided with a radial shaft F, which is rotatably supported in the bearings D, before referred to, being held in place by 50 a collar G on its end.

Bicycles of ordinary construction and without alteration are arranged in a circle around

the above-described supporting-frame, each being supported by one of the yokes in any suitable or desired manner, the preferred 55 form being described as follows: Upon the head of the bicycle-frame is securely fixed the head-clamp H, which is provided on one side with the ear I. Similarly fixed upon the seat-post of the bicycle-frame is 60 the seat-post clamp J, which is provided with a rearwardly-projected ear which passes out between the rear forks of the frame and is then turned to one side. To these two ears I and J are pivotally attached the two arms 65 of the bicycle-yoke E. A brace K connects the rear arm of the bicycle-yoke with the axle of the rear wheel, being pivotally attached to the arm of a clamp L and to the axle by a plate M. It will be observed that the guy- 70 rods C are attached to the whirl-ring B in pairs, one pair running from the top of the ring to one bicycle and the next pair running from the bottom of the ring to the next bicycle, thus necessitating the capability of 75 angular adjustment of the yokes to the bicycles. In Fig. 4 there is shown in full lines the position of the guy-rods, yoke, and brace when the guy-rods run from the bottom of 80 the whirl-ring and in dotted lines the positions of the parts when the guy-rods run from the top of the whirl-ring, and it is seen that the clamp L in the latter case is slightly nearer the bicycle to compensate for the difference in inclination of the guy-rods. Thus 85 it is seen that the bicycle-frame is supported in a vertical plane, but permitted to move vertically and oscillate in said plane about the yoke-shaft F as a center to compensate for accidental or intended inequalities or 90 curvatures of the floor over which the bicycles run.

In order that the bicycles may run properly in the predetermined circular path, I have provided means for setting and holding the 95 front fork in its proper position, and for this purpose I have made a front-fork yoke N, provided with clamps O O on the end of its two arms adapted to be fixedly secured to the arms of the front fork. The rear end of the 100 front-fork yoke N is provided with a slot P, cut in the arc of a circle, of which the center is the center line of the bicycle-head. Fixedly secured to the lower chord of the bicycle-

frame is the clamp Q, which is provided on its under side with a bolt R, which extends down through the slot P, and by the screwing up of which the front-fork yoke N may be secured in the proper position to hold the front wheel at the proper angle to make the bicycle run smoothly in the circular path required by any given diameter of bicycle-whirl.

5 A baby or child seat S is or may be supported on the guy-rods over the yoke-shaft bearings.

If desirable, spring connections T may be interposed between the successive pairs of guy-rods.

10 15 The whirl is especially adapted to be propelled by the bicycle-riders themselves, or, if preferred, it may be driven from the whirl-wheel B in any usual or suitable manner.

Having thus described my invention, I 20 claim as new and desire to secure by Letters Patent of the United States—

1. In a bicycle-whirl, the combination with a center post, of a plurality of bicycles, and means for supporting said bicycles in a circle around said post consisting of a frame rotatably mounted on said post and carrying at its periphery radial bearings and bicycle-yokes supporting the bicycles and provided, respectively, with radial shafts supported in 25 30 said bearings, each yoke having two arms at-

tached respectively to the head and seat-post of the bicycles substantially as described.

2. In a bicycle-whirl, the combination with a rotatably-supported frame provided at its periphery with a plurality of radially-pivoted 35 bicycle-yokes and a plurality of bicycles arranged in a circle and supported in said yokes, each yoke having two arms attached respectively to the head and seat-post of the bicycles substantially as described.

3. In a bicycle-whirl, the combination with a rotatably-supported frame, of a bicycle and a bicycle-yoke carried by said frame, having two arms adapted to be attached, respectively, to the head and seat-post of said bicycle and a 40 brace extended from the rear arm to the axle of the rear wheel of said bicycle, substantially as described.

4. The combination with a rotatably-supported frame, of a bicycle and a bicycle-yoke 45 attached rigidly to the head and seat-post of said bicycle, and radially pivoted to said frame, substantially as described.

In testimony whereof I affix my signature in presence of two witnesses.

PERCY L. SMITH.

Witnesses:

THOMAS C. RUTLAND,
HORACE VAN EVERNS.
